UNITED STATES PATENT OFFICE.

WALTER S. WIERO, OF RAVENSDALE, WASHINGTON.

COLLAPSIBLE BOAT.

Application filed April 1, 1922. Serial No. 548,656.

To all whom it may concern:

Be it known that I, WALTER S. WIERO, a citizen of the United States of America, and resident of the town of Ravensdale, in the county of King, State of Washington, have invented certain new and useful Improvements in Collapsible Boats, of which the following is a specification.

My invention relates to collapsible boats. The object of my invention is to provide a boat so constructed that it may be taken apart and collapsed into a package of such a size that it may be conveniently transported particularly upon ordinary passenger automobiles. It is also an object to keep the weight small enough and the size of the package of such character that it may also be carried by a single man for ordinary distances.

The features of my invention which I believe to be new and upon which I desire to obtain a patent will be hereinafter set forth and then particularly defined by the claims.

The accompanying drawings show my invention embodied in the type of construction which I now prefer to use.

Figure 1 is a top plan view of the boat when expanded and in position of use.

Figure 2 is a side elevation of the boat in condition for use.

Figure 3 is a central transverse section with one end thereof broken away.

Figure 4 shows, in perspective, a portion of the side and bottom together with one of the ribs, to better illustrate the manner of securing the parts together.

Figure 5 is a cross section on an enlarged scale showing the upper end of a rib and the manner of securing the parts together at this point.

The construction of my boat is one employing a collapsible frame work which may be assembled in the form of a boat, over which is then placed a cover or skin composed of canvas or any other suitable fabric. The bottom of the boat employs four plates 1, each being of thin material as sheet metal and representing a quarter section of the bottom of the boat. These plates when in use are positioned with edges in contact so that the combination outlines the body of the boat. The line of division between the plates is along the longitudinal and transverse central axes. The two plates at opposite sides of the longitudinal central

line at one end of the boat are secured together by hinges as 10, so as to fold in one direction. Two of these plates which lie at one side of the longitudinal axis are secured together by hinges 11, which however, are so placed as to fold the plates in the opposite direction from the hinges 10. The end edges of the two plates at the other side of the boat are, however, not hinged together but may be secured together when the bottom has been opened by means of a bolt, as 12, or any other suitable securing means.

To stiffen these plates against buckling or bending in a vertical direction, I provide them with ribs as 13 positioned in a general radial direction from the center of the boat bottom and preferably stamped from the body of the plate, forming the bottom. These ribs when so formed would be of substantially U-shape in cross section. The exact shape of these ribs and in fact whether they are stamped in the manner referred to, or secured in other ways, is not the material part of my invention.

In conjunction with a bottom so constructed and to give it greater strength as a whole, I employ a grating composed of longitudinal bars 21 and transverse bars 20, which are secured together to form a rigid whole. This is of such size that when centrally placed on the bottom of the boat its corners will extend substantially to, and if desired somewhat beyond, the centers of the respective quadrants of the bottom; so that when placed thereon there will be no appreciable tendency to buckle along the line of joining of the plates 1. It is not contemplated that any material load, or at least any concentrated load, be applied to and carried by the bottom outside of the margin of this grating.

The plates forming the bottom have flaps or eyes 3 forming sockets for the reception of feet formed upon the lower ends of the ribs 30. These are spaced apart along the sides and ends of the boat at whatever distance is found necessary or desirable to properly support the sides of the boat. As indicated these are formed of flat bars bent into a shallow U-shape so that when their ends are secured to the bottom of the plate a suitable socket is formed for the reception of the feet at the lower end of the ribs 30. These feet 31 are formed by bending the body of the rib laterally and are designed

to fit snugly in the socket piece 3. The ribs 20 may be of any suitable cross section. As indicated in Figures 3, 4, and 5 these ribs are bent so that in cross section they are of 5 a U or semi-circular shape. At their upper ends these ribs are provided with a slot, as 32, and their upper ends are connected by bars, as 4, which are provided with buttons 10 spaced so that the stems of these buttons 15 may enter the slots 32 and the ribs be thus supported each from the other and held in definite relation. The rods or bars 4 which form the gunwale member of the boat are also provided with buttons, pins, or other analogous securing means 40 to which the edges of the canvas or other fabric covering may be secured. The bars 4 are designed to be of approximately the same length as the bottom sections, 1. The ends which abut 20 at the center of the length of the boat are secured together, as by means of a ferrule 41, into which the ends enter. Similar ferrules, as 42, may be used for securing the other ends of the side bars to the end bars 4.

25 The frame thus formed is covered with a canvas or other fabric form as 5. This is shaped so as to fit snugly over the frame and it is provided with means complementary to the members carried by the bar 4 and indicated at 40 whereby the canvas cover may be securely held in place and yet removed when desired.

30 At each side of the boat I have provided what may be termed emergency or safety floats. These consist each of a pneumatic tube as 6 which is held in place against the side of the boat and external thereto by means of a flap 60 of fabric, secured at its upper and lower edges to the canvas cover of 40 the boat. Preferably at least one edge of this flap is detachably secured so that the pneumatic tube may be inserted and removed at will. These would ordinarily be placed somewhere at or a little above the 45 normal draft line of the boat. Their purpose is to form additional displacement members which will be brought into action when the boat is tipped or rocked to one side, thus adding a safety feature to prevent 50 overturning of the boat. Also they will provide buoys which would still have sufficient capacity to keep the boat afloat in case the canvas cover should be perforated and the boat filled with water.

55 A boat constructed in accordance with the accompanying drawings and the above description may be folded into a size of which the grating represents the largest member. This and the bottom sections folded together 60 with the canvas cover and the ribs, may be inserted in any suitable carrying case and

the whole conveniently carried on the running board of an automobile.

What I claim as my invention is:

1. A collapsible boat comprising a bottom composed of plate sections hinged together, ribs, means for detachably connecting the ribs with the bottom, bars detachably connectible with the upper ends of said ribs and a detachable fabric cover fitting over 70 the entire frame formed by the other parts when set up.

2. A collapsible boat comprising a bottom composed of plate sections hinged together, the bottom having rib-receiving sockets about 75 its edge and ribs having feet fitting said sockets, bars engageable with the upper ends of said ribs and a fabric cover for the frame thus formed.

3. A collapsible boat comprising a bottom composed of plate sections hinged together, a stiffening frame for placing upon the bottom sections when opened into position of use, ribs, means for detachably securing the ribs to the bottom, rods connecting the upper ends of said ribs and a fabric cover for the frame thus formed.

4. A collapsible boat comprising a bottom composed of plate sections hinged together, ribs, means for detachably securing 90 the ribs to the bottom comprising sockets on the bottom and feet on the ribs, the upper end of the ribs being slotted, marginal rods having projecting pins adapted to enter the said slots in the ribs, and a fabric cover for the 95 frame thus formed.

5. A collapsible boat comprising a bottom composed of plate sections hinged together, ribs, means for detachably securing the ribs to the bottom comprising sockets on the bottom and feet on the ribs, the upper end of the ribs being slotted, marginal rods having 100 projecting pins adapted to enter the said slots in the ribs, a fabric cover for the frame thus formed, said marginal rods and the 105 fabric cover having complementary button-like devices for securing the two together.

6. A collapsible boat comprising a bottom composed of metal plate sections hinged together along edges to form the outline of 110 the boat bottom, said sections having stiffening ribs pressed therein and radiating from the center of the bottom, a stiffening grating of a size that when centrally placed upon the bottom will extend substantially to the centers of all the bottom plates, ribs secureable to the edges of the bottom and a fabric cover for the frame thus formed.

Signed at Seattle, King County, Washington, this 27th day of March, 1922.

WALTER S. WIERO
